CALCULATING MACHINE

Conrad Luttröpp, Stockholm, Sweden, assignor
of one-half to Anders Lindahl, Stockholm,
Sweden

Application October 18, 1927, Serial No. 226,968

54 Claims. (Cl. 235—63)

Calculating machines are already known in which multiplication may be effected by registering the multiplicand in the main counting register as many times as the multiplier indicates, that is to say, by adding the multiplicand to itself a number of times equal to that indicated by the multiplier. This operation may be facilitated by having the calculating machine provided with a so called tabulator, that is to say, with means for moving the main counting register or totalizer step by step from one digit value to another, in which case the multiplicand is first registered in the counting register as many times as is indicated by the unit figure of the multiplier, said register being then displaced one step to the left, whereupon the multiplicand is registered as many times as the ten digit of the multiplier indicates, etc. In order to avoid the necessity of setting up the multiplicand on the key board for every actuation of the main counting register, calculating machines have been designed which are provided with a so called repeating key which, when depressed, prevents the counting members from being returned to their starting position so that the number set up will be retained in the selector. This provides semi-automatic multiplication, being automatic for one digit only, as it is necessary to manually move the carriage one step when passing from one digit column to the next.

The present invention relates to calculating machines having a selector and a plurality of keys for operating said selector and has for its principal object to provide means whereby automatic multiplication may be obtained not only with multipliers comprising a simple digit but also with multipliers comprising two or more digits, without the necessity of manually operating the main counting register in passing from a digit column to the next.

In accordance with the invention and my preferred embodiment thereof, I provide a calculating machine having what I term a primary section and a secondary section and means whereby the primary section is operated under control of the secondary section. The primary section includes a primary key board, a selector operated by the primary keys of the primary key board, and in which items may be set up, a totalizer, and item transfer mechanism for transferring an item set up in the selector to the totalizer one or more times. The secondary section includes a secondary key board having secondary keys and a secondary selector operated by the keys of the secondary key board for setting up an item in

the secondary selector. In performing multiplication one factor is set up in the primary section and another factor is set up in the secondary section. I provide novel and improved means for repeated operation of the primary section under control of the secondary section to transfer an item set up in the primary selector to the totalizer in accordance with the item set up in the secondary section. My calculating machine includes means for positively moving the various mechanisms. The secondary section is zeroized by positive means, as distinguished, for example, from elastic means, and preferably by the automatic operation of power mechanism. In the zeroizing operation, transfer from digit to digit is positively effected. The totalizer is stepped by positive means. By providing positive drive of the various parts I obtain quicker operation than has heretofore been possible, and I eliminate friction and provide an adequate force at all times to insure accuracy.

In the preferred embodiment of the invention said secondary selector comprises a carriage movable step by step in either direction and a plurality of members, as horizontal racks, slidably mounted on said carriage and each engaging a disk presenting circumferentially disposed numerals.

The invention further comprises stopping means actuated by the keys of said secondary section for limiting the movement of said members or racks. Such stopping means may comprise a set of pivotally mounted levers each connected with a member or rack. I also provide means to effect a horizontal step by step movement of said secondary selector during the setting operation as well as during the zeroizing operation, means operated by the secondary series of keys for locking said members or racks in zero position, and means for rendering the item transfer mechanism ineffective during the stepping of the totalizer.

The zeroizing means is preferably operated by the driving shaft of the machine, whereas the step by step movement of the secondary selector during the setting operation is preferably controlled by springs.

The invention further comprises other novel features as will more fully appear from the following detailed description.

In the following detailed description the invention will be described as embodied in a calculating machine made up in part of a known ten-key calculating machine of a special type, that is to say, to a machine in which one key only

is provided for each figure. It is to be noted, however, that the invention may also be applied to calculating machines of other types including multi-key calculating machines, that is to say, machines in which there is a row of keys for each digit.

The machine described is driven by an electric motor though the invention is not restricted to motor-driven machines but may also be applied to manually operated machines.

In the accompanying drawings:

Fig. 1 is an assembly view, somewhat diagrammatic, showing a calculating machine provided with mechanism in accordance with the present invention, a section of the machine being shown only to an extent necessary for a clear understanding of the invention;

Fig. 2 is a top view of a part of the calculating machine, the casing being broken away, and showing what I term the secondary selector;

Fig. 3 is a bottom view of the secondary selector;

Fig. 4 is a perspective view of parts of the secondary selector mechanism;

Fig. 5 is a perspective view of a part of the mechanism of Fig. 4;

Fig. 6 is a front view of part of the machine showing tabulating or stepping mechanism;

Fig. 7 is a view of part of the mechanism of Fig. 1; and

Fig. 8 is a view of another part of the mechanism of Fig. 1.

In the following description the secondary key board is considered as being at the front part of the machine, and the expressions "forwards" and "backwards" as well as "front" and "rear" are used with regard thereto. The expressions "right" and "left" refer to the machine as seen from the front.

As will more clearly appear as the description proceeds, my preferred form of calculating machine embodying the invention has parts similar to the calculating machine described in my Patent No. 1,662,526, granted March 13, 1928. My present calculating machine incorporates the essential features of the machine set forth in that patent and I have added mechanism for setting up an independent numerical factor and cooperating parts for correlating the additional mechanism to the mechanism described in the aforesaid patent. For purposes of ease of definition, ease of description, and ease of understanding, I herein classify the present machine as comprising, in general, a primary section, a secondary section and operating mechanism. The primary section is essentially the calculating machine of the aforesaid patent and includes primary item set-up mechanism, item transfer mechanism and a totalizing mechanism including the usual tens transfer mechanism. The secondary section includes a secondary set-up mechanism. If two numbers are to be multiplied, one is set up in the primary section, the other in the secondary section, and driven parts perform the multiplication, in the course of which the mechanism of the primary section is controlled in certain respects by the mechanism of the secondary section and the product is registered in the totalizer, all as will more fully appear.

In view of the similarity of the primary section of the machine of this application to the machine of my aforesaid patent, it will suffice to more briefly describe and show the primary section herein than would otherwise be the case, since

reference may be had to the aforesaid patent for details of construction, wherefore I will explain the primary mechanism herein only so far as is necessary to an understanding of the invention.

The primary section

The primary section comprises primary keys 250 mounted on primary key board 10 and operable by means of mechanism including rods 251 to set up digits in an oscillatory primary sector 11. It also comprises spindles 13 and what I term a counting drum 12. The key board 10 contains ten keys corresponding to the digits 0 to 9, respectively, and a number of other controlling keys one of which only is shown, namely the repeating key 15, the other controlling keys not being necessary for a clear understanding of the invention. The primary selector 11 comprises, briefly, groups of movable stops or tongues, the tongues of each group being arranged one above the other and corresponding to the different digit keys. The tongues are set into operative positions by depressing the keys, the selector 11 being at the same time moved step by step. Co-operating with said groups of tongues are the counting spindles 13, which are movable vertically into positions determined by the tongues projected in the selector. Each counting spindle 13 carries a pinion 16 adapted to be actuated by the drum 12 when positioned laterally adjacent the drum and when the latter is rotated by transmission of movement thereto from the main driving shaft 17 of the machine by way of arm 18, link 19, gear segment 20, and gear wheel 21. The gear 21 rotates a miter gear 252, through a one-way clutch, which operates mechanism for rotating a vertical shaft on which drum 12 is mounted. Preferably a clutch and oppositely rotatable miter gears are used, as disclosed in my aforesaid patent by means of which drum 12 can be rotated in either direction. The drum 12 comprises discs provided with different numbers of teeth and arranged one above the other and which correspond in order to the different unit digits. The upper end of each counting spindle 13 is engaged by a rotatable spindle 22 in such a manner that the spindle 13 can move axially but can not rotate in relation to the spindle 22. At its upper end each spindle 22 carries a bevel gear 23 to transmit the movement to the main counting register or totalizer 29 which is located in the carriage 30 movable step by step in either direction. The transfer of digits set up to totalizer 29 takes place by way of the bevel gear 24 engaging the bevel gear 23, the intermediate shaft 25 carrying said bevel gear 24, the gearing 26, 27 at the opposite end of shaft 25 and the intermediate wheel 28. It will be seen that the primary keys 250, the primary selector 11 and the intermediate actuating mechanism constitute set-up mechanism for setting up digits in the selector; and that gear sector 20, drum 12, the intermediate mechanism between gear sector 20 and drum 12, spindles 13, the mechanism moving the same and the parts 22, 23, 24, 25, 26, 27 and 28 constitute item transfer mechanism for transferring the items set up in the primary selector to the totalizer.

The means for moving the totalizer carriage 30 step by step in either direction is of the type shown in my Patent No. 1,671,537. In the embodiment shown the means for moving the carriage in one direction comprises, as shown, a double rack 31 secured to the carriage 30 on the lower edge thereof and having two series of

The secondary key board

100 designates a frame adapted to be applied to the previously described primary section of the calculating machine and what is the calculating machine proper of my aforesaid Patent No. 1,662,526 in front of the primary key board 10. Mounted in said frame 100 are ten keys corresponding to the digits 0 to 9 inclusive (see especially Figs. 2 and 4). Each secondary key comprises a rod 101 guided in a corresponding opening in the frame 100. The head 102 of each key carries a figure. At its lower end each rod 101 is pivoted to one end of a bell crank lever 104 journalled in the frame by a pin 103. Journalled on a shaft 106 rigid in the frame is a set of bell crank levers 107 mounted close to each other on said shaft. The number of said levers 107 is equal to the number of the secondary keys. There are, thus, ten levers 107. Such levers 107 will hereinafter be termed "stop levers" on account of their action. The lever 104 associated with each key rod 101 is connected at its other end to the lower end of a corresponding one of said stop levers 107 by means of a link 108. By means of springs 109 secured to the frame 100 and to the individual levers 104 the keys are maintained in elevated position. By depressing a key the corresponding stop lever 107 will be turned upwards.

As the repeating key forms an essential part of the device according to the present invention, said key will be described in detail. In the embodiment shown key 15 comprises a rectangular sheet metal plate carrying two depending rods 40 guided in the plate of key board 10 and each pivoted at its lower end to a bell crank lever 41, each bell crank lever being pivotally mounted on a fixed shaft. Said bell crank levers are connected to each other at their lower ends by means of a link 42. Loosely mounted on a shaft 43 secured to the machine frame is a fork-shaped arm 44, one leg 35 of which engages a pin 46 on the link 42 and is held thereagainst by means of a spring 45 secured to one of the levers 41, the other leg of the arm 44 being extended so as to bear against a roller 47 carried at the free end of an arm 48 secured to a shaft 49 journalled in the machine frame as, for instance, by means of brackets 50. The key rods 40 are each provided with a notch 51 by means of which the key, when depressed, will be retained in depressed position in engagement with the underside of the key board 10. Springs 52 secured at one end to each of the levers 41 and at the other end to the key board 10 tend to return the key into its raised position. When key 15 is depressed and locked in its depressed position by notches 51 under the key board 10, the long arms of the bell-crank levers 41 are moved toward the front of the machine, carrying with them connecting link 42 and its pin 46. This movement releases the short end of lever 44 and permits spring 45 to pull on this lever and cause its long end to depress roller 47 and shift bell-crank 48 to connect the motor, as hereafter described.

60 As long as the key 15 remains locked lever 44 will follow bell-crank 48 under the influence of spring 45, automatically repeating the connection to the motor drive for multiplication.

65 The repeating key is in well known manner connected to the selector 11 so that upon the depression of the repeating key the selector and the counting spindles will be prevented from returning to their starting position as in my Patent No. 1,662,526. To illustrate this I have shown bar 256 and rod 257 attached to bell crank 41 and it will be understood that these are connected to the mechanism shown and described in that patent for maintaining items in the primary selector for repeated transfer to the totalizer.

5 100 and guide 254 is a pawl 33 adapted to mesh with one row of teeth of the rack 31. Pivotedly mounted on the upper portion of bar 32 by means of the pin 34 is another pawl 35. A tension spring 36 is secured to the machine frame 10 and the lower end of pawl 35. A pin 37 mounted on member 33 engages an elongated slot 38 in the pawl 35. Those ends of the two pawls 33 and 35 which are adapted to mesh with the rack 31 are so shaped that, when the rod 32 is moved upwards, the pawl 35 is first brought into engagement with a tooth of one of the rows of teeth to cause a displacement of the rack together with the carriage 30. The movement is restricted to one step only due to the pawl 33 engaging a tooth 20 of the other row of teeth of the rack 31. For further details, reference may be had to my aforesaid Patent No. 1,671,537.

25 As the repeating key forms an essential part of the device according to the present invention, said key will be described in detail. In the embodiment shown key 15 comprises a rectangular sheet metal plate carrying two depending rods 40 guided in the plate of key board 10 and each pivoted at its lower end to a bell crank lever 41, each bell

30 crank lever being pivotally mounted on a fixed shaft. Said bell crank levers are connected to each other at their lower ends by means of a link 42. Loosely mounted on a shaft 43 secured to the machine frame is a fork-shaped arm 44, one leg 35 of which engages a pin 46 on the link 42 and is held thereagainst by means of a spring 45 secured to one of the levers 41, the other leg of the arm 44 being extended so as to bear against a roller 47 carried at the free end of an arm 48 secured to a shaft 49 journalled in the machine frame as, for instance, by means of brackets 50. The key rods 40 are each provided with a notch 51 by means of which the key, when depressed, will be retained in depressed position in engagement with the underside of the key board 10. Springs 52 secured at one end to each of the levers 41 and at the other end to the key board 10 tend to return the key into its raised position. When key 15 is depressed and locked in its depressed position by notches 51 under the key board 10, the long arms of the bell-crank levers 41 are moved toward the front of the machine, carrying with them connecting link 42 and its pin 46. This movement releases the short end of lever 44 and permits spring 45 to pull on this lever and cause its long end to depress roller 47 and shift bell-crank 48 to connect the motor, as hereafter described.

40 50 As long as the key 15 remains locked lever 44 will follow bell-crank 48 under the influence of spring 45, automatically repeating the connection to the motor drive for multiplication.

45 55 The repeating key is in well known manner connected to the selector 11 so that upon the depression of the repeating key the selector and the counting spindles will be prevented from returning to their starting position as in my Patent No. 1,662,526. To illustrate this I have shown bar 256 and rod 257 attached to bell crank 41 and it will be understood that these are connected to the mechanism shown and described in that patent for maintaining items in the primary selector for repeated transfer to the totalizer.

Means for stepping the secondary selector to the left

60 Attached to the front side of the guide plate 112 (see Figs. 2 and 4) is an arm 130 carrying at its free end a pin 131 in engagement with an elongated slot 132 formed in a movable member or bridge 133. Pivoted to said bridge 133 is one end of a bell crank lever 135 rotatably mounted in the frame 100 at 134, Fig. 2. This lever 135 due to its

function will hereinafter be termed "releasing" lever. The other or free end of releasing lever 135 is adapted to co-operate with that locking lever 123 which for the time being has its front 5 end just under the free end of lever 135. The broad end of bridge 133 terminates in close proximity to the lower arms of the stop levers 107 and is at this place of such a width as to be moved to the left every time that any of the stop 10 levers 107 are turned upwards due to operation of the corresponding key. Pivotaly connected to the bridge 133 is one end of an angularly shaped pawl 136 pivoted to the under side of the guide 112 at 140. It is thus seen that the bridge 133 is 15 guided on the one hand by its engagement with the arm 130 and on the other hand by its engagement with the pawl 136. Loosely mounted on the same pin 140 as the pawl 136 is another angularly shaped pawl 141 directed in opposite direction 20 to the pawl 136. The pawls 136 and 141 co-operate with each other by means of a pin 142 carried by the pawl 141 and held in engagement with the pawl 136 by means of a spring 143 secured to the guide 112. The pawls 136 and 141 are adapted to 25 engage a rack 144 secured to the secondary selector carriage 113. Normally, the pawl 141 is in mesh with said rack 144, whereas the pawl 136 is out of engagement therewith. A spring 145 connects the secondary selector carriage 113 to the 30 frame 100, as at 146, said spring thus tending to move the secondary selector to the left against the action of the locking means above described.

Means for stepping the secondary selector to the right

Pivotaly mounted at 150 on the under side of the guide plate 112 is a lever 151 carrying at its free end a pawl 153 which may turn on the pin 152. Pawl 153 is adapted to mesh with the rack 144 but is normally held out of engagement therewith. Furthermore the arm 151 is provided with a fixed tooth 154 as well as with a stop 155 against which latter the pawl 153 is normally held by means of a spring 156. Furthermore, the arm 151 carries a guiding pin 157 engaging a slot 160 in a link 161 forming part of the zeroizing means to be hereinafter described and carrying at its foremost end an abutment 162. The link 161 constitutes an operating member for stepping the 50 secondary selector and performs a reciprocating movement during the zeroizing operation in the manner to be hereinafter described and will in this movement slide to and fro guided by the pin 157. An arm 163 likewise belonging to the zeroizing means is pivotaly connected to a stop arm 164 the free end 165 of which constitutes a stop. A spring 166 connects the arm 163 to the stop arm 164, and an abutment 167 on the arm 163 limits the angular position of the arm 163 and the stop 55 arm 164 in relation to each other in the one direction. The arm 164 which in the zeroizing operation is normally out of engagement with the guiding pin 157 and the abutment 162 will be turned upwards when the selector 113 is to be 60 stepped to the right, whereby its free end 165 is lifted in between said guiding pin 157 and said abutment 162 (see Fig. 3), causing the reciprocating link 161 to positively bring with it the arm 151 causing the selector 113 to be moved one step 65 in the manner to be described below.

The driving mechanism

Mounted at a suitable point on the base is an electric motor 170 (see Fig. 1) from which motion 75 is transmitted to the driving shaft 17 of the ma-

chine, for instance in the following manner. Attached to the motor shaft 172 is a worm 173 and meshing with said worm is a worm wheel 175 secured to a central operating shaft 174 journalled in the base. The ratio of the worm gearing is so 5 chosen as to give the shaft 174 a number of revolutions suitable for the operation of the machine. Journalled on a fixed pin 176 in the base is an arm 177 carrying a rotatable disc 180 which co- 10 operates with a cam disc 181 eccentrically mounted on the shaft 174. The arm 177 is pulled by a spring 182 in such manner as to keep the disc 180 in permanent engagement with the cam disc 181. On rotation of the motor it will be seen that the free end of the arm 177 will be given a reciprocating 15 movement. Said free end of the arm 177 engages a roller 184 carried by the arm 18 secured to the main driving shaft 17 of the machine, and as a result said shaft 17 will be caused to oscillate when the motor is running. From the electric 20 motor 170 the motion is also transmitted to the zeroizing means hereinafter described, on the one hand by means of a link 161 pivotaly mounted eccentrically on the end of the shaft 174 and, on the other hand, by means of the link 185 pivotaly 25 mounted to the arm 177 at a suitable point 186 in relation to the turning axle 176. When the motor is running, said two links 185 and 161 will, consequently, also perform a reciprocating movement, the points of mounting of said links being suitably chosen with regard to the movements which the links are to effect and which will be described hereinbelow.

From the motor 170 the motion is also transmitted to the shaft 49. To this end shaft 49 35 carries an arm 60 pivotaly connected at its free end to a fork 61 extending downwardly to the shaft 174. The arm 61 is part of well-known mechanism for controlling the operation of the motor and its effect on the actuated mechanism. 40 While, for sake of illustration, I have shown one means of motor control in Figs. 1, 7 and 8, it will be understood that various known motor control mechanisms may be employed. In the arrangement shown, the motor is started by a switch 45 thrown into electric contact on depression of the repeating key 15. This is done by arranging a linkage 260 to close a switch 261 of known kind mounted on shaft 174. Preferably the starting mechanism of the motor is so constructed that 50 the motor, after having been started, will continue its rotation during a given period of time, for example, 40 to 60 seconds, whether or not the repeating key 15 has been returned to its raised position in the meantime and the contact controlled by said key has been broken. This can be accomplished by having the motor cut itself out after a given number of revolutions from the time of contact. To stop the actuation of the calculating machine I may use any of various 55 known types of clutches as, for example, a pawl and ratchet clutch in which a ratchet wheel 262 (Fig. 7) carried by the worm wheel 175 cooperates with a pawl 263 carried on the separate driven part of shaft 174, which pawl 263 cooperates with an abutment 264 on arm 61. A roller 265 or other part connected to or forming part of arm 61 is arranged to be contacted by cam disc 62 mounted on the driven part of shaft 174. When the motor is running and repeating key 15 depressed, the 60 action of cam 62 in pushing arm 61 upwardly and the action of spring 45 in urging arm 61 downwardly will cause the shaft 49 together with the arm 48, the roller 47 and the fork-shaped arm bearing on the latter to move to and fro. Cam 65 70

62 moves abutment 264 into position to be contacted by pawl 263 to throw the clutch out of engagement, but so long as the repeating key is depressed, spring 45 urges arm 60 and consequently 5 abutment 264 downwardly before contact therewith of pawl 263 would occur so that the upper part of pawl 263 passes over abutment 264 and disengagement does not take place.

10 *Shifting of the selectors subsequent to zeroizing the racks of the secondary selector*

10 Mounted on a loose shaft 190 held in the frame 100 is a member 191a to an arm of which the link 185 is pivoted. Pivotal mounted in an arm of 15 a member 191 is a catching hook 192 actuated by a spring 193 secured to the member 191. The members 191 and 191a move together and may be said to constitute a double-armed cross-piece to 20 the one arm of which the link 185 is pivoted and to the other arm of which the catching hook 192 is pivoted. The catching hook 192 is so arranged in relation to the selector 113, that, when the latter in the setting operation is moved its first step to the left, in the manner to be hereinafter described, the catching hook 192 is right below the extreme left hand rack 114 so that the hook 192, during the zeroizing operation, is brought into engagement with the teeth 115 on the under side of said rack 114 due to its reciprocating movement 25 30 in a manner to be described later on.

The arm 163 above referred to as forming part of the zeroizing mechanism is loosely journaled on the shaft 190 and extends on the rear side of said shaft in the form of an arm 194 bent upwards which is located in front of the rack 114 farthest to the left, when the selector 113 is moved its first step to the left. Furthermore, said arm 194 is so located as to be in alignment with the rear ends of the racks 114 when said racks are in 35 their zero positions. Consequently, the arm 194 will be turned backwards when the rack 114 lying right in front of the arm is moved backwards beyond its zero position in the manner to be described below, causing, amongst other things, the 40 45 upward turning of the stop arm 164 referred to above.

Pivots connected with the arm 194 at 196 is another arm 195 suitably guided as at 197 which co-operates with means for moving the totalizer 50 carriage 30 step by step. Journaled in the frame of the primary section of the calculating machine proper as at 198 is an angularly shaped catching lever 201 carrying at its one end a hook 202. The other end of the said lever 201 is operated by the driving shaft 17 of the machine, for instance by means of a slot 203 formed in said 55 end of the lever 201 and a pin 204 on the arm 18 engaging said slot. Movable connected with the driving bar 32 of the tabulator as at 207 is a ratchet 60 65 206 normally held in a forward position by means of a spring 208 and which is adapted to be operated by the arm 195 to be pushed rearwardly through hole 209.

The zeroizing mechanism further comprises 65 means for lifting the repeating key 15 out of engagement with the plate of key board 10, when the zeroizing operation is completed. The rack 114 farthest to the left is provided with an abutment 210 which, when said rack is in zero position, bears on the end of the lower arm of a lever 211 journaled in the machine frame at 43. The upper arm of said lever 211 is adapted to engage an abutment 212 disposed on the under side of the repeating key 15, said upper arm lying behind 70 75 said abutment, when the repeating key is de-

pressed. When, in the zeroizing operation, the rack 114 farthest to the left is moved backwards beyond its zero position, in a manner to be hereinafter described, the abutment 210 of said rack 114 will, as a result, turn the lever 211 whereby the upper end of said lever on account of the engagement with the abutment 212 will move the repeating key forward so as to bring the key rods 40 out of engagement with the key board plate to allow the key 15 to be lifted by the action of the 10 springs 52.

Furthermore, it is necessary that the counting members of the primary section of the calculating machine are out of operative engagement with the driving shaft when the racks 114 by 15 power transmitted from the motor 170 are moved backwards beyond their zero positions, as during said last-mentioned movement the totalizer must not be operated. To this end the link 19 engages the driving toothed segment 20 by means of a 20 slot 215 in the link and a pin 216 on the segment. The link 19 extends forwardly and is shaped so that its free end normally engages a pin 217 on the arm 195. It is evident that, when the arm 195 is moved backwards, the link 19 will be lifted 25 out of engagement with the segment 20 and may slide freely on the pin 216 during the next operation of the machine.

The operation of the mechanism is as follows:

On depressing a key on the secondary key 30 board 100 the stop lever 107 connected with said key is turned upwards by means of the corresponding bell crank lever 104 and the link 108. When the stop lever 107 is thus turned upwards the bridge 133 is moved a distance to the left. 35 This will cause the upper arm of the releasing lever 135 to turn downwardly into engagement with that locking lever 123 lying farthest to the left which causes a release of the corresponding rack 114 so that the latter will now be free to 40 move forwardly under the action of the spring 124, until its front end strikes the actuated stop lever 107; that is to say, it will be moved a distance corresponding to the key pressed down. When the rack 114 is moved forwardly the pinion 45 118 engaging the teeth 116 on said rack and, consequently, also the figure wheel 121 rigidly connected to said pinion are rotated a corresponding number of steps, so that the figure set up will be visible through a window in the frame. 50 When the bridge 133 is moved to the left the pawls 136 and 141 are actuated in such manner, that the pawl 141 is first brought out of engagement with the rack 144 whereby the latter together with the entire selector 113 will be free 55 to move to the left under the action of the spring 145. This movement, however, is limited to approximately half a pitch as the pawl 136 which has previously engaged the rack will prevent further movement due to its oblique surface engaging in a tooth space of the rack. When then the key 102 is released the bridge 133 will return to starting position by the action of the spring 143 causing disengagement of the pawl 136 so that the selector 113 becomes free to move to 60 the left the remainder of a pitch by the action of the spring 145, until the pawl 141 engages the next tooth space of the rack 144. The depression of a key has, therefore, set the first rack 114 and the figure wheel connected thereto in conformity with the key pressed down and has moved the selector 113 as a whole a step to the left so that the next rack 114 with its locking lever 123 has been brought in front of the releasing lever 135. Then the operation may be repeated, until 70 75 80 85 90 95 100 105 110 115 120 125 130 135 140 145 150 155 160 165 170 175 180 185 190 195 200 205 210 215 220 225 230 235 240 245 250 255 260 265 270 the desired number has been set up in the selector 113.

Assuming that a multiplication is to be performed, for instance, that the number 456 is to be multiplied by the number 23. One factor, as 5 456, is then set up on the primary key board 10, and the other factor, that is 23, on the secondary key board 100. Accordingly, the number 456 is set up in the primary selector 11 and the 10 number 23 in the secondary selector 113, the latter assuming a position in which the two figure wheels 121 lying farthest to the left will show, as seen from the left, the figures 2 and 3, respectively, while the second rack 114, as seen from 15 the left, lies in register with the catching hook 192 and exactly in front of the angular arm 194. The repeating key 15 is now depressed and locked by the notches 51 engaging the plate of primary key board 10. This will lock the primary selector 20 11 in the set position by the mechanism and in the manner described in my aforesaid Patent No. 1,662,526 and, furthermore, the circuit of the electric motor 170 is closed so that the latter is started. By means of the worm gearing 173, 175 and the cam device 180, 181 a reciprocating movement is imparted to the arm 177 causing an oscillation of the driving shaft 17. Such a movement is also imparted to the catching hook 192 by means of the link 185 and the 25 cross-piece 191 to cause the hook 192 by engagement in the teeth 115 to move the second rack 114 as counted from the left backwardly step by step. For each backward step of the rack 114 and, consequently, for each oscillation of the driving shaft 17 the number 456 set up in 30 the primary selector 11 will be transferred to the totalizer 29. When the rack 114 is moved three steps, its rear end will strike against the arm 194. The rack 114 is then once more actuated by the catching hook 192, before the secondary selector is moved one step to the right. This additional actuation of the rack to the rear of zero position, however, does not cause any permanent displacement of the rack, as the tooth 35 116 that would correspond to the position of the rack after the completion of said last-mentioned actuation, is omitted so that the rack will be returned to zero position by the action of the spring 124 in which position the locking lever 40 123 engages the foremost tooth 116.

During this temporary displacement of the rack 114 into engagement with the arm 194, the latter is swung backwards causing the following movements. The arm 195 connected to arm 194 45 is moved backwards causing the pin 217 thereon to lift the link 19 out of engagement with the driving gear segment 20 thereby disengaging the primary section of the calculating machine during this additional stroke. The backward displacement of the arm 195 also causes the ratchet 206 to be pushed rearwardly and the upper rearwardly extending finger thereof to pass rearwardly well through the hole 209 in the bar 32 of the tabulator. For each of the preceding three 50 steps of the rack 114 the catching lever 201 has made an oscillation under the action of the driving shaft 17 by means of the slot and pin connection 203, 204. This movement, however, has not resulted in any actuation of the tabulator, as 55 the ratchet 206 has not projected through the hole 209 in the bar 32 and, consequently, has not been moved into the path of movement of the catching lever 201. Now, however, when the upper finger of ratchet 206 is moved rearwardly 60 through hole 209 in bar 32, the catching lever 201 65

will on its return stroke engage the finger of ratchet 206 and carry the bar 32 upwardly thus effecting a displacement of the totalizer carriage 30 one step. During this additional stroke of the rack 114 the secondary selector 113 is also displaced one step to the right which takes place as follows. During the zeroizing operation the link 161 performs a reciprocating movement sliding on the guiding pin 157 of the arm 151. When the arm 194 is swung backwards, the arm 163 10 rigidly connected thereto is turned upwards so that the stop arm 164 connected to said arm 163 with its end or stop 165 is lifted up between the guiding pin 157 and the abutment 162 of the link 161. When, as a result, the link 161 during said 15 additional stroke of the rack 114 is moved backwards it will bring with it the arm 151 whereby the pawl 153 connected to said arm 151 will be brought into engagement with the rack 144 to move said rack together with the secondary selector 113 one step to the right. In this displacement the tooth 154 will act as a brake, and the movement of the arm 151 with its pawl 153 is so adjusted as to limit the displacement to one step. It will be seen that the arm 164 may be 20 said to constitute a control member for controlling the stepping of the secondary selector, the control member being actuated by movement of the racks, and the actual stepping being caused by the operation of link 161.

At the end of this additional stroke of the rack the link 19 again engages the driving segment 20 to again bring the primary section of the calculating machine into engagement with the driving shaft. It is thus seen that the rack 114 farthest to the left is just above the catching hook 192, and the operation is continued in the same manner until also this rack is zeroized. During the additional stroke of said extreme left hand rack the repeating key 15 will be released by the abutment 210 on said rack operating the lever 211, causing it to move the repeating key 15 forward on account of its engagement with the abutment 212 on said key, whereby the rods 40 will be 35 disengaged from the key board 10 and the key will be raised by the action of the springs 52.

On zeroizing the second rack 114 as seen from the left product 3×456 has been obtained in the totalizer and on zeroizing the rack 114 farthest to the left the product 20×456 , is obtained that is to say, the final result will be 40 23×456 .

What I claim is:

1. In a calculating machine comprising a primary selector, a primary key board having digit keys, means operable by said keys for setting up digits in the primary selector, a totalizer, primary item transfer mechanism for transferring items from the primary selector to the totalizer, motor mechanism, and mechanism forming a power transmission connection between said motor mechanism and said primary item transfer mechanism, the combination therewith of a secondary selector, a secondary key board having digit keys, means operated by the last-mentioned keys for setting up digits in the secondary selector, means operated by said motor mechanism to successively zeroize the digits set up in the secondary selector unit by unit, means controlling operation of the primary item transfer mechanism in accordance with the operation of the secondary selector, and means controlled by said secondary selector and operated by said motor mechanism to step said totalizer after the zeroizing of each digit and on 55 60 65 70 75 80 85 90 95 100

transfer from digit to digit in the secondary selector.

2. In a calculating machine comprising a primary selector, a primary key board having digit keys, means operable by said keys for setting up digits in the primary selector, a totalizer, primary item transfer mechanism for transferring items from the primary selector to the totalizer, motor mechanism, and mechanism forming a

10 power transmission connection between said motor mechanism and said primary item transfer mechanism including separable parts for making or breaking the power transmission connection, the combination therewith of a secondary

15 selector, a secondary key board having digit keys, means operated by the last mentioned keys for setting up digits in the secondary selector, means operated by said motor mechanism to successively zeroize the digits set up in the secondary

20 selector unit by unit, means controlling operation of the primary item transfer mechanism in accordance with the operation of the secondary selector, means controlled by said secondary selector for disconnecting said separable parts and

25 means for stepping said totalizer while said parts are separated.

3. In a calculating machine comprising a primary selector, a primary key board having digit keys, means operable by said keys for setting up

30 digits in the primary selector, a totalizer, primary item transfer mechanism for transferring items from the primary selector to the totalizer, motor mechanism, and mechanism forming a power transmission connection between said motor

35 mechanism and said primary item transfer mechanism including separable parts for making or breaking the power transmission connection, the combination therewith of a secondary selector, a secondary key board having digit keys,

40 means operated by the last-mentioned keys for setting up digits in the secondary selector, means operated by said motor mechanism to successively zeroize the digits set up in the secondary selector unit by unit, means controlling operation of

45 the primary item transfer mechanism in accordance with the operation of the secondary selector, means controlled by said secondary selector for disconnecting said separable parts and means controlled by said secondary selector and operated

50 by said motor mechanism to step said totalizer while said parts are separated.

4. In a calculating machine comprising a primary selector, a primary key board having digit keys, means operable by the keys for setting up

55 digits in the primary selector, a totalizer, and primary item transfer mechanism for transferring items from the primary selector to the totalizer, the combination therewith of a secondary selector, a secondary key board having digit keys,

60 means operable by the last-mentioned keys for setting up digits in the secondary selector, means to successively zeroize the digits set up in said secondary selector unit by unit, and positively operated reciprocating means controlled by said

65 secondary selector to step said totalizer.

5. In a calculating machine including a primary section comprising item set-up mechanism, a totalizer and item transfer mechanism; the combination therewith of a secondary section comprising item set-up mechanism including movable elements adapted to be moved and stopped to set up items; means for operating said primary section in cycles under control of said movable elements of the secondary section comprising a motor and power transmitting means

operable by said motor to actuate said item transfer mechanism once during a cycle; means for producing one or more extra movements of said movable elements; means for stepping said totalizer during such extra movement under control of said secondary section; and means for rendering the item transfer mechanism inoperative during such extra movement when the totalizer is stepped.

6. In a calculating machine including a primary section comprising item set-up mechanism, a totalizer and item transfer mechanism; the combination therewith of a secondary section comprising item set-up mechanism; totalizer stepping mechanism; operating mechanism having revolutions of movement; and means controlled by said secondary section for causing said operating mechanism to operate said item transfer mechanism during certain one or more revolutions and means controlled by said secondary 10 section for connecting said operating mechanism to said totalizer stepping mechanism during certain other one or more revolutions.

7. A calculating machine including a primary section comprising item set-up mechanism, a totalizer and item transfer mechanism; a secondary section comprising item set-up mechanism; totalizer stepping mechanism; operating mechanism having revolutions of movement; and means controlled by said secondary section for causing 15 said operating mechanism to operate said item transfer mechanism but not said stepping mechanism during certain one or more revolutions; and means controlled by said secondary section to operate said stepping mechanism but not said 20 item transfer mechanism during certain other one or more revolutions.

8. In a calculating machine including a primary section comprising item set-up mechanism, a totalizer and item transfer mechanism; a secondary section comprising item set-up mechanism; and a motor; the combination therewith of a shaft driven by said motor; power transmitting means comprising separable parts operable to actuate said item transfer mechanism once for each revolution of said shaft; means for stepping said totalizer during a revolution of said shaft; means to separate said separable parts for rendering said item transfer mechanism inoperative during said last-mentioned revolution when the totalizer is 40 stepped; means whereby the operation of the power transmitting means is controlled by said secondary section; and means whereby the totalizer stepping means is controlled by said secondary section.

9. In a calculating machine the combination with a primary section comprising a ten-key primary key board, a primary selector, means operated by the keys of said primary key board for setting up an item in said primary selector, 45 a totalizer and item transfer mechanism for transferring the item set up to the totalizer; of a secondary section comprising a ten-key secondary key board, a secondary selector including a movable carriage and means operated by the keys of said secondary key board for moving said carriage and setting up an item in said secondary selector; means for operating said primary section in cycles under control of said secondary section comprising a motor, and power 60 transmitting means operable by said motor to actuate said item transfer mechanism once during a cycle; means for producing an extra movement of said secondary selector; means for stepping said totalizer during such extra movement; 65

70

75

75

and means for rendering the item transfer mechanism inoperative during such extra movement when the totalizer is stepped.

10. In a calculating machine the combination with a primary section comprising a ten-key primary key board, a primary selector, means operated by the keys of said primary key board for setting up an item in said primary selector, a totalizer and item transfer mechanism for transferring the item set up to the totalizer; of a secondary section comprising a ten-key secondary key board, a secondary selector including a movable carriage and means operated by the keys of said secondary key board for moving said carriage and setting up an item in said secondary selector; totalizer stepping mechanism; operating mechanism having revolutions of movement; and means controlled by said secondary section for causing said operating mechanism to operate said item transfer mechanism during certain one or more revolutions and means for connecting said operating mechanism to said totalizer stepping mechanism during certain other one or more revolutions.
15. 11. A calculating machine including a primary section comprising a ten-key primary key board, a primary selector, means operated by the keys of said primary key board for setting up an item in said primary selector, a totalizer and item transfer mechanism comprising separable parts for transferring the item set up to the totalizer; a secondary section comprising a ten-key secondary key board, a secondary selector and means operated by the keys of said secondary key board for setting up an item in said secondary selector; totalizer stepping mechanism; operating mechanism having revolutions of movement; and means controlled by said secondary section for connecting and disconnecting said separable parts to cause said operating mechanism to operate said item transfer mechanism but not said stepping mechanism during certain one or more cycles; and means to operate said stepping mechanism but not said item transfer mechanism during certain other one or more cycles.

12. In a calculating machine, the combination with a casing, a guide mounted in said casing, a carriage slidably mounted on said guide, a plurality of straight racks mounted in said carriage, and means to longitudinally move said racks to set up digits, of means to return said racks unit by unit and beyond zero position and means for stepping said carriage controlled by movement of a rack on its return stroke beyond zero position.

13. In a calculating machine, the combination with a casing, a guide mounted in said casing, a carriage slidably mounted on said guide, a plurality of straight racks mounted in said carriage, and means to successively longitudinally move said racks to set up digits, of means to successively return said racks unit by unit and beyond zero position and means for successively stepping said carriage between the zeroizing of digits of adjacent racks actuated by successive movements of the racks on their return strokes beyond zero position.

14. In a calculating machine, the combination with a casing, a guide mounted in said casing, a carriage slidably mounted on said guide, a plurality of straight racks mounted in said carriage, and means to longitudinally move said racks to set up digits, of means to return said racks unit by unit and beyond zero position comprising a rotatable shaft and means operated by

said shaft to move a rack one unit for a revolution of said shaft and means for stepping said carriage operated by movement of a rack on its return stroke beyond zero position.

15. In a calculating machine, the combination with a casing, a guide mounted in said casing, a carriage slidably mounted on said guide, a plurality of straight racks mounted in said carriage, and means to longitudinally move said racks to set up digits, of means to return said racks unit by unit and beyond zero position comprising a rotatable shaft and means operated by said shaft to move a rack one unit for a revolution of said shaft and means for stepping said carriage operated by revolution of said shaft and controlled by movement of a rack on its return stroke beyond zero position.

16. In a calculating machine, a casing, a guide mounted in said casing, a carriage slidably mounted on said guide, a plurality of straight racks mounted in said carriage, means to longitudinally move said racks to set up digits, a rotatable shaft, means to return said racks unit by unit operated by said rotatable shaft and means for stepping said carriage comprising a ratchet mounted on said carriage, a pawl member mounted on said guide, an operating member, a control member, means operated by said shaft for reciprocating said operating member and means for interposing said control member between said operating member and said pawl member.

17. In a calculating machine, a casing, a guide mounted in said casing, a carriage slidably mounted on said guide, a plurality of straight racks mounted in said carriage, means to longitudinally move said racks to set up digits, means to return said racks unit by unit and means for stepping said carriage comprising a ratchet mounted on said carriage, a pawl member mounted on said guide, an operating member, a control member, means for moving said operating member and means for interposing said control member between said operating member and said pawl member.

18. In a calculating machine, a casing, a guide mounted in said casing, a carriage slidably mounted on said guide, a plurality of straight racks mounted in said carriage, means to longitudinally move said racks to set up digits, means to return said racks unit by unit and means for stepping said carriage comprising a ratchet mounted on said carriage, a pawl member mounted on said guide, an operating member, an electric motor connected to reciprocate said operating member, a control member and means operated by movement of said racks for interposing said control member between said operating member and said pawl member.

19. In a calculating machine, a casing, a guide mounted in said casing, a carriage slidably mounted on said guide, a plurality of straight racks mounted in said carriage, means to longitudinally move said racks to set up digits, means to return said racks unit by unit and means for stepping said carriage comprising a ratchet mounted on said carriage, a pawl member mounted on said guide, an operating member, positive acting means to reciprocate said operating member, a control member and means operated by certain one or more of said racks on their return strokes beyond zero position for interposing said control member between said operating member and said pawl member.

20. In a calculating machine, a casing, a guide mounted in said casing, a carriage slidably

- mounted on said guide, a plurality of straight racks mounted in said carriage, a series of aligned stops mounted in said casing, keys for selectively positioning said stops, means comprising ratchet mechanism operated on depression of the keys to move said racks successively past said stops, spring operated means controlled by depression of the keys to move the racks in alignment with a selected stop, means to return said racks unit 10 by unit and means for returning said carriage comprising a pawl member mounted on said guide, an operating member, a control member, means for moving said operating member and means for interposing said control member between said operating member and said pawl member.
21. In a calculating machine comprising a primary selector, a primary key board having digit keys, means operable by the keys for setting up digits in the primary selector, a totalizer including a movable carriage and primary item transfer mechanism for transferring items from the primary selector to the totalizer, the combination therewith of a secondary selector including a movable carriage, the last-mentioned carriage being independently movable with respect to the carriage of the totalizer, a secondary key board having digit keys, means operable by the last-mentioned keys for moving the carriage of the secondary selector and setting up digits in the secondary selector, a rotatable motor shaft, means operated by said shaft to successively zeroize the digits set up in said secondary selector unit by unit and means operated by said shaft and controlled by said secondary selector to step said totalizer on transfer from digit to digit in the secondary selector.
22. In a calculating machine including a primary section comprising item set-up mechanism, a totalizer and item transfer mechanism; a secondary section comprising item set-up mechanism including a plurality of movable members; and adapted to be set to correspond to items a rotatable motor shaft; the combination therewith of means operated by said shaft for actuating said item transfer mechanism under control of said secondary section; and mechanism independent of said item transfer mechanism and operated by said shaft and controlled by said secondary selector by abutting relation with said movable members for stepping said totalizer.
23. A calculating machine including a primary section comprising item set-up mechanism, a totalizer and item transfer mechanism; a secondary section comprising a selector carriage, movable members on said carriage adapted to be set to correspond to items and means for selectively moving and stopping said movable members to set up items in the secondary section; a carriage for said totalizer; means for actuating said item transfer mechanism in accordance with an item set up in said secondary section; and means for automatically moving said selector carriage and said totalizer carriage in the same direction under control of said secondary section.
24. In a calculating machine, a casing, a guide mounted in said casing, a carriage slidably mounted on said guide, a plurality of straight racks mounted in said carriage, a series of aligned stops mounted in said casing, keys for selectively positioning said stops, means comprising ratchet mechanism operated on depression of the keys to move said racks successively past said stops, spring-operated means controlled by depression of the keys to move the racks in alignment each with a selected stop, a rotatable shaft, means operated by said shaft to return said racks unit by unit and means for returning said carriage comprising a ratchet mounted on said carriage, a pawl member mounted on said guide, an operating member operated by said shaft, a control member and means for interposing said control member between said operating member and said pawl member.
25. In a calculating machine, a casing, a guide mounted in said casing, a carriage slidably mounted on said guide, a plurality of straight racks mounted in said carriage, a series of aligned stops mounted in said casing, keys for selectively positioning said stops, means comprising ratchet mechanism operated on depression of the keys to move said racks successively past said stops, spring-operated means controlled by depression of the keys to move the racks in alignment each with a selected stop, a rotatable shaft, means operated by said shaft to return said racks unit by unit and means for returning said carriage comprising a ratchet mounted on said carriage, a pawl member mounted on said guide, an operating member operated by said shaft, a control member and means for interposing said control member between said operating member and said pawl member.
26. A calculating machine including a primary section comprising item set-up mechanism, a totalizer and item transfer mechanism; a secondary section comprising a selector carriage, movable members on said carriage and key-operated means for moving said movable members to set up items; a carriage for said totalizer; a rotatable shaft; means for actuating said item transfer mechanism in accordance with the item set up in said secondary section; a rotatable shaft; and means operated by said rotatable shaft and controlled by movement of said movable members for moving said selector carriage and said totalizer carriage in the same direction.
27. A calculating machine including a primary section comprising item set-up mechanism, a totalizer and item transfer mechanism; a secondary section comprising a selector carriage, movable members on said carriage and key-operated means for moving said movable members to set up items; a carriage for said totalizer; a rotatable shaft; means for actuating said item transfer mechanism in accordance with an item set-up in said secondary section comprising a power connection between said shaft and said item transfer mechanism; means actuated by said shaft for automatically moving said selector carriage and said totalizer carriage in the same direction under control of said secondary section; and means controlled by said secondary section for disconnecting said power connection when the carriages are moved.
28. In a calculating machine, a casing, a guide mounted in said casing, a carriage slidably mounted on said guide, a plurality of straight racks mounted in said carriage, a series of aligned stops mounted in said casing, keys for selectively positioning said stops, means comprising ratchet mechanism operated on depression of the keys to move said racks successively past said stops, spring-operated means controlled by depression of the keys to move the racks in alignment each with a selected stop, a rotatable shaft, means operated by said shaft to return said racks unit by unit and means for returning said carriage comprising a ratchet mounted on said carriage.

a pawl member mounted on said guide, an operating member operated by said shaft, a control member and means actuated by abutting contact with a rack for moving the control member into contact with the operating member.

29. In a calculating machine comprising a primary selector, a primary key board having digit keys, means operable by said keys for setting up digits in the primary selector, a totalizer, primary item transfer mechanism for transferring items from the primary selector to the totalizer, motor mechanism, mechanism forming a power transmission connection between said motor mechanism and said item transfer mechanism, the combination therewith of a secondary selector including straight racks, a secondary key board having digit keys, means operated by said keys to successively move said racks to selective positions to set up digits in said secondary selector, means operated by said motor mechanism to successively zeroize the digits set up in the secondary selector by successively returning said racks unit by unit, means controlling operation of the item transfer mechanism in accordance with the action of the secondary selector, and means for controlling the stepping of the totalizer comprising a member moved by abutting contact therewith of a rack at the end of the return stroke thereof during the zeroizing operation on transfer from digit to digit.

30. In a calculating machine comprising a primary selector, a primary key board having digit keys, means operated by said keys for setting up digits in the primary selector, a totalizer, item transfer mechanism for transferring items from the primary selector to the totalizer, motor mechanism, mechanism forming a power transmission connection between said motor mechanism and said item transfer mechanism, the combination therewith of a secondary selector including straight racks, a secondary key board having digit keys, means operated by said keys to successively move said racks to selective positions to set up digits in said secondary selector, means operated by said motor mechanism to successively zeroize the digits set up in the secondary selector by successively returning said racks unit by unit, means controlling operation of the item transfer mechanism in accordance with the action of the secondary selector, and means for controlling the stepping of the totalizer operated by a rack during the zeroizing operation on transfer from digit to digit at the end of the return stroke of said rack.

31. A calculating machine including a primary section comprising item set-up mechanism, a totalizer and item transfer mechanism; a secondary section comprising a movable selector carriage, a plurality of racks mounted side by side on said carriage and means for moving and positioning said racks to set up items; a movable carriage for said totalizer; means for actuating said item transfer mechanism in accordance with an item set up in said secondary section; and means for automatically moving said selector carriage and said totalizer carriage in the same direction under control of said secondary section.

32. A calculating machine including a primary section comprising item set-up mechanism, a totalizer and item transfer mechanism; a secondary section comprising a movable selector carriage, a plurality of racks mounted side by side on said carriage and means for moving and positioning said racks to set up items including a

plurality of aligned stops; a movable carriage for said totalizer; means for actuating said item transfer mechanism in accordance with an item set up in said secondary section; and means for automatically moving said selector carriage and said totalizer carriage in the same direction under control of said secondary section.

33. A calculating machine including a primary section comprising item set-up mechanism, a totalizer and item transfer mechanism; a secondary section comprising a movable selector carriage, a plurality of lengthened racks mounted side by side on said carriage, means for moving and positioning said racks to set up items including a plurality of aligned stops and means to align the racks one at a time with the line of stops; a movable carriage for said totalizer; means for actuating said item transfer mechanism in accordance with an item set up in said secondary section; and means for automatically moving said selector carriage and said totalizer carriage in the same direction under control of said secondary section.

34. A calculating machine including a primary section comprising item set-up mechanism, a totalizer and item transfer mechanism; a secondary section comprising a movable selector carriage, a plurality of lengthened racks mounted side by side on said carriage, means for moving and positioning said racks to set up items including spring release mechanism and a plurality of aligned key-operated stops and means to align the racks one at a time with the line of stops; a movable carriage for said totalizer; means for actuating said item transfer mechanism in accordance with an item set up in said secondary section; and means for automatically moving said selector carriage and said totalizer carriage in the same direction under control of said secondary section.

35. A calculating machine including a primary section comprising item set-up mechanism, a totalizer and item transfer mechanism; a secondary section comprising a movable selector carriage, a plurality of parallel racks mounted side by side on said carriage, means for moving said racks transversely to the path of movement of the selector carriage and for positioning the racks including a plurality of aligned stops; a carriage for said totalizer movable independently of said selector carriage; means for actuating said item transfer mechanism in accordance with an item set up in said secondary section; and means for automatically moving said selector carriage and said totalizer carriage under control of said secondary section.

36. A calculating machine including a primary section comprising item set-up mechanism, a totalizer and item transfer mechanism; a secondary section comprising a movable selector carriage, a plurality of parallel racks mounted side by side on said carriage, means for moving said racks transversely to the path of movement of the selector carriage and for positioning the racks including a plurality of aligned stops and means to align the racks one at a time with the line of stops; a carriage for said totalizer movable independently of said selector carriage; means for actuating said item transfer mechanism in accordance with an item set up in said secondary section; and means for automatically moving said selector carriage and said totalizer carriage under control of said secondary section.

37. A calculating machine including a primary section comprising item set-up mechanism, a

totalizer and item transfer mechanism; a secondary section comprising a movable selector carriage, a plurality of parallel racks mounted side by side on said carriage, means for moving said racks transversely to the path of movement of the selector carriage and for positioning the racks including spring release mechanism and a plurality of aligned key-operated stops and means to align the racks one at a time with the line of stops; a carriage for said totalizer movable independently of said selector carriage; means for actuating said item transfer mechanism in accordance with an item set up in said secondary section; and means for automatically moving said selector carriage and said totalizer carriage under control of said secondary section.

38. A calculating machine including a primary section comprising item set-up mechanism, a totalizer and item transfer mechanism; a secondary section comprising a movable selector carriage, a plurality of straight parallel racks mounted side by side on said carriage, means for moving said racks transversely to the path of movement of the selector carriage and for positioning the racks and a plurality of indicator wheels mounted side by side on a common axis transverse to the racks and movable with the racks; a movable carriage for said totalizer; means for actuating said item transfer mechanism in accordance with an item set up in said secondary section; and means for automatically moving said selector carriage and said totalizer carriage in the same direction under control of said secondary section.

39. A calculating machine including a primary section comprising item set-up mechanism, a totalizer and item transfer mechanism; a secondary section comprising a movable selector carriage, a plurality of straight parallel racks mounted side by side on said carriage, means for moving said racks transversely to the path of movement of the selector carriage and positioning the racks including spring release mechanism and a plurality of aligned key-operated stops and means to align the racks one at a time with the line of stops, and a plurality of indicator wheels mounted side by side on a common axis transverse to the racks and movable with the racks; a movable carriage for said totalizer; means for actuating said item transfer mechanism in accordance with an item set up in said secondary section; and means for automatically moving said selector carriage and said totalizer carriage in the same direction under control of said secondary section.

40. A calculating machine including a primary section comprising item set-up mechanism, a totalizer and item transfer mechanism; a secondary section comprising a movable selector carriage, movable members on said carriage, a plurality of coaxially mounted indicator wheels rotatable by said movable members, means for moving said movable members to set up and indicate items; a movable carriage for said totalizer; means for actuating said item transfer mechanism in accordance with an item set up in said secondary section; and means for automatically moving said selector carriage and said totalizer carriage in the same direction under control of said secondary section.

41. A calculating machine including a primary section comprising item set-up mechanism, a totalizer and item transfer mechanism; a secondary section comprising a movable selector carriage, a plurality of racks mounted on said car-

riage, a plurality of coaxially mounted indicator wheels geared to said rack and disposed side by side, means for moving said movable members to set up and indicate items; a movable carriage for said totalizer; means for actuating said item transfer mechanism in accordance with an item set up in said secondary section; and means for automatically moving said selector carriage and said totalizer carriage in the same direction under control of said secondary section.

42. In a calculating machine, a guide, a carriage slidably mounted on said guide, a plurality of calculating members mounted in said carriage, means for automatically moving said members step by step comprising a rotatable shaft, a member continuously reciprocated during movement of said shaft, and means comprising a member movable by the calculating members into the path of movement of the reciprocating member to step the carriage.

43. In a calculating machine, a guide, a carriage slidably mounted on said guide, a plurality of calculating members mounted in said carriage, means for automatically moving said members step by step comprising a rotatable shaft, a member continuously reciprocated during movement of said shaft, and means comprising a pivoted member in the path of movement of said calculating members and movable into the path of movement of said reciprocating member to step the carriage.

44. In a calculating machine, a guide, a carriage slidably mounted on said guide, a plurality of calculating members mounted in said carriage, means for moving said members step by step comprising a rotatable shaft, a member continuously reciprocated during movement of said shaft, a totalizer carriage, means movable when a calculating member has a given position to cause movement of the reciprocating member to step the first-mentioned carriage and means responsive to the last mentioned movable means to move said totalizer carriage.

45. In a calculating machine, a guide, a carriage slidably mounted on said guide, a plurality of calculating members mounted in said carriage, means for moving said members step by step comprising a rotatable shaft, a member continuously reciprocated during movement of said shaft, a totalizer carriage, means for stepping the first mentioned carriage comprising a member movable into the path of movement of the reciprocating member due to movement of the calculating members, and means for stepping the totalizer carriage actuated by movement of the member movable into the path of the reciprocating member.

46. In a calculating machine including a casing, a guide mounted in said casing, a carriage slidably mounted on said guide, a plurality of racks mounted in said carriage, and means to move said racks to set up digits, the combination therewith of a rotatable shaft, means to return said racks unit by unit operated by said rotatable shaft and means for stepping said carriage comprising a ratchet mounted on said carriage, a pawl member, means operated by said shaft for reciprocating said operating member and means for interposing said control member between said operating member and said pawl member.

47. In a calculating machine including a casing, a guide mounted in said casing, a carriage slidably mounted on said guide, a plurality of racks mounted in said carriage, means to move said racks to set up digits, and means to return said

racks unit by unit, the combination therewith of apparatus for stepping said carriage comprising a ratchet mounted on said carriage, a pawl member mounted on said guide, an operating member, 5 a control member, means for moving said operating member and means for interposing said control member between said operating member and said pawl member.

48. In a calculating machine including a casing, a guide mounted in said casing, a carriage 10 slidably mounted on said guide, a plurality of racks mounted in said carriage, means to move said racks to set up digits, and means to return said racks unit by unit, the combination therewith of apparatus for stepping said carriage comprising a ratchet mounted on said carriage, a pawl member mounted on said guide, an operating member, an electric motor connected to reciprocate said operating member, a control member 15 and means operated by movement of said racks for interposing said control member between said operating member and said pawl member.

49. In a calculating machine including a casing, a guide mounted in said casing, a carriage 20 slidably mounted on said guide, a plurality of racks mounted in said carriage, means to move said racks to set up digits, and means to return said racks unit by unit, the combination therewith of apparatus for stepping said carriage comprising a ratchet mounted on said carriage, a pawl member mounted on said guide, an operating member, an electric motor connected to reciprocate said operating member, a control member 25 and means operated by certain one or more of said racks on their return strokes beyond zero position for interposing said control member between said operating member and said pawl member.

40 50. In a calculating machine comprising a primary selector, a primary key board having a single key for each digit, means operable by said keys for setting up digits in the primary selector, totalizing mechanism including a movable carriage, means for transferring items from the primary selector to the totalizing mechanism, motor mechanism, mechanism forming a power transmission connection between the motor mechanism and said primary item transfer mechanism, the combination therewith of a secondary selector including a movable carriage, said last-mentioned carriage being movable independently of said totalizer carriage, a secondary key board having a single key for each digit, means operated by the last-mentioned keys for moving and setting up digits in the secondary selector, means operated by said motor mechanism to successively zeroize digits set up in the secondary selector, and means controlled by the 45 secondary selector for disconnecting said power transmission connection.

51. In a calculating machine comprising a primary selector, a primary key board having a single key for each digit, means operable by said 60 keys for setting up digits in the primary selector, totalizing mechanism including a movable carriage, means for transferring items from the primary selector to the totalizing mechanism, motor mechanism, mechanism forming a power transmission connection between the motor mechanism and said primary item transfer mechanism, the combination therewith of a secondary selector

including a movable carriage, said last-mentioned carriage being movable independently of said totalizer carriage, a secondary key board having a single key for each digit, means operated by the last-mentioned keys for moving and setting up digits in the secondary selector, means operated by said motor mechanism to successively zeroize digits set up in the secondary selector, and means actuated by the secondary selector for controlling the operation of the primary selector and associated parts. 5

52. In a calculating machine comprising a primary selector, a primary key board having a single key for each digit, means operable by said keys for setting up digits in the primary selector, totalizing mechanism including a movable carriage, means for transferring items from the primary selector to the totalizing mechanism, motor mechanism, mechanism forming a power transmission connection between the motor mechanism and said primary item transfer mechanism, the combination therewith of a secondary selector including a movable carriage, said last-mentioned carriage being movable independently of said totalizer carriage, a secondary key board having a single key for each digit, means operated by the last-mentioned keys for moving and setting up digits in the secondary selector, means operated by said motor mechanism to successively zeroize digits set up in the secondary selector, and means actuated by the secondary selector for controlling said power transmission connection and shifting the totalizer carriage and the secondary selector. 10 15 20 25 30

53. In a calculating machine comprising a primary selector, a primary key board having a single key for each digit, means operable by said keys for setting up digits in the primary selector, totalizing mechanism including a movable carriage, means for transferring items from the primary selector to the totalizing mechanism, motor mechanism, mechanism forming a power transmission connection between the motor mechanism and said primary item transfer mechanism, the combination therewith of a secondary selector including a movable carriage, said last-mentioned carriage being movable independently of said totalizer carriage, a secondary key board having a single key for each digit, means including a plurality of racks operated by the last-mentioned keys for moving and setting up digits in the secondary selector, means operated by said motor mechanism to successively zeroize digits set up in the secondary selector, and means abutting against said racks for controlling movement of the totalizer carriage. 35 40 45 50 55 60

54. A calculating machine including a primary section comprising item set-up mechanism, a totalizer and item transfer mechanism; a secondary section comprising a movable selector carriage, a plurality of racks mounted side by side on said carriage and means for moving and positioning said racks to set up items; a carriage for said totalizer movable independently of the first-mentioned carriage; means for actuating said item transfer mechanism in accordance with an item set up in said secondary section; and means for automatically moving said selector carriage and said totalizer carriage under control of said secondary section. 65 70
